UNITED STATES PATENT OFFICE.

HOHSON S. SHIMIZU, OF CHICAGO, ILLINOIS, ASSIGNOR TO ROBERTS & SCHAEFER COMPANY, OF CHICAGO, ILLINOIS, A CORPORATION OF ILLINOIS.

APPARATUS FOR HANDLING COAL.

1,355,512.

Specification of Letters Patent. Patented Oct. 12, 1920.

Application filed September 17, 1918. Serial No. 254,405.

To all whom it may concern:

Be it known that I, HOHSON S. SHIMIZU, a subject of the Emperor of Japan, residing at Chicago, in the county of Cook and State 5 of Illinois, have invented a certain new and useful Improvement in Apparatus for Handling Coal, of which the following is a specification.

My invention relates to hoisting apparatus particularly intended for use in connection with coal, and has for its object among other things to provide means whereby the hoisting bucket can be simultaneously tilted and moved bodily laterally so as to 10 bring the mouth of the bucket under the hopper while the mouth is substantially horizontal during the hoisting operation.

My invention is illustrated more or less diagrammatically in the accompanying 20 drawings, wherein

Figure 1 is a side elevation in part sectional view of the apparatus with the bucket at the lower end of its excursion;

Fig. 2 is a cross section on the line 2—2 25 of Fig. 1;

Fig. 3 is a cross section on the line 3—3 of Fig. 1.

Like parts are indicated by the same letters in all the figures.

30 A is a hopper supplied from cars running on the track A¹, and A² is the discharge port of such hopper. The hopper is preferably made long enough so as to operate in connection with two buckets and the apparatus 35 is preferably arranged so that one bucket is at the top while the other is at the bottom and intended to balance their respective weights.

B, B are two vertical shafts in which the 40 buckets move. Each is provided with two guide rails B¹, B¹ which extend from the top to near the bottom of the shafts.

C is the bucket provided with the apron C¹ and the upwardly projecting straps C². 45 C². Near the upper end of the buckets are the rollers C³, C³, two on each side and along the body of the buckets are the guide bars C⁴, C⁴, two on each side adapted each pair to engage the guide rail B¹ and hold 50 the bucket in the upright position as it moves vertically.

D, D are two short laterally diverging rails secured to the guide rail B¹ and provided each with a cut-away portion D¹ to

permit one of the guide bars C⁴ to pass 55 therethrough. D² are somewhat similar laterally diverging guide rails which are secured in position but sufficiently removed from the rail B¹ to permit one of the straps to pass between such rail B¹ and the laterally diverging guide rails D². The rollers C³, C³ are adapted to overhang and ride upon the outer surface of the rails D¹, D² and thus they tend to tilt the top of the bucket laterally. 60

E is a shaft secured to the rear of the bucket and carrying at either end the rollers E¹, E¹ adapted each to be received between the lower rear guide rails E², E². These 70 guide rails are laterally deflected at their lower ends and thus the bucket as it descends tends to move laterally.

F, F are somewhat similar rollers on the forward part of the bucket associated with the two lower forward guide rails F¹, F¹ and 75 adapted to pass between them. The lower ends of these guide rails are deflected laterally thus also tending to move the bucket laterally.

By the joint action of the three sets of 80 lower laterally deflected guide rails, the bucket is carried bodily laterally and its portion or mouth is tilted laterally so as to bring it ultimately responsive to such action into a position where the mouth though in horizontal position on the vertical run is inclined and substantially parallel with the discharge port of the hopper. 85

G is a gate mounted on rollers G¹, G¹ which are adapted to ride on the tracks G², G² so that the gate can travel back and forth across the path of the coal or other material as it flows from the hopper port. G³ is a lip on the bucket and G⁴ a projection on the gate. These two engage as the bucket 90 mouth moves downwardly and the gate is moved to open the passage from the hopper to the bucket. G⁵ is a weight mounted on the rope G⁶ which travels over the pulley G⁷ and is attached to the upper end 100 of the gate thus tending to keep it in the closed position. G⁸, G⁸ are pocket-shaped lugs on the gate so placed that as the bucket descends into position the straps C² will drop each into one of said pockets so that 105 when the bucket begins to ascend it is positively connected with the gate so as to force it upwardly at least for a considerable por-

tion of its excursion after which the weight will be sufficient to close it.

Certain other features are illustrated in the drawings, but as they are the subject 5 matter of another application Serial No. 235,234, filed May 18, 1918, and have nothing to do with the invention here sought to be covered, they will not be described. They have to do with the discharge port, 10 gate and chute for the bucket and the means of controlling the same.

J, J are strengthening bars within and along the top of the bucket and J¹ cross bars, J² an arm secured to the inside of the 15 bucket at J³ connected with the cross bar at J⁴ and provided with a cable ring J⁵ whereby the bucket may be moved by means of a rope or hoisting engine.

It will be understood that my drawings 20 are to be taken in a sense diagrammatic as they are intended simply to be illustrative and point out the general features of construction, although a working apparatus can be made by following fairly closely the 25 drawings.

The use and operation of my invention are as follows:—

A bucket with a horizontal upper opening will naturally hold the largest amount 30 of material safely. When such a bucket is moved laterally to bring it under the hopper, the depth of the pit will necessarily be relatively greater than in the case where a tilting bucket is used. To bring 35 the bucket properly under or into proper relation with the port of the hopper, it is desirable to move the bucket laterally. The benefit of both of these conditions can be obtained by simultaneously moving the 40 bucket laterally to bring it under the hopper and by tilting it so as to bring its normally horizontal mouth into an inclined position to register with the port of the hopper. This latter port is itself preferably in 45 an inclined position. To get this result I have invented means whereby the bucket is held in upright position with its mouth horizontal on its vertical course but is simultaneously tilted and moved laterally at the 50 lower end of its excursion. The nature and degree of such lateral movement and such tilting can be varied to any desired extent and I have shown but one form of device to bring about this result.

55 I claim:

1. A coal handling plant comprising a hopper having a discharge port, a bucket having an inlet port, means for moving the bucket vertically, means for moving it laterally bodily beneath the hopper at the lower 60 end of its excursion while at the same time tilting its upper portion about a moving pivot toward the hopper port so as to bring the two ports into register.

65 2. A coal handling plant comprising a

hopper having a discharge port, a bucket having an inlet port, means for moving the bucket vertically, means for moving it laterally bodily beneath the hopper at the lower 70 end of its excursion while at the same time tilting its upper portion about a moving pivot toward the hopper port so as to bring the two ports into register and a cut-off gate adapted to move responsive to the bucket movement. 75

3. A coal handling plant comprising a hopper having a discharge port, a bucket having an inlet port, means for moving the bucket vertically, means for moving it laterally bodily beneath the hopper at the lower 80 end of its excursion while at the same time tilting its upper portion about a moving pivot toward the hopper port so as to bring the two ports into register and a cut-off gate adapted to move responsive to the bucket 85 movement and to leave a free passage from the hopper to the bucket while the ports are in register.

4. A coal handling plant comprising a hopper having a discharge port, a bucket 90 having an inlet port, means for moving the bucket vertically, means for moving it laterally bodily beneath the hopper at the lower end of its excursion while at the same time tilting its upper portion toward the hopper port so as to bring the two ports into 95 register and a cut-off gate adapted to move responsive to the bucket movement and means whereby the bucket by its motion positively moves the gate in both directions. 100

5. A coal handling plant comprising a hopper having a discharge port, a bucket having an inlet port, means for moving the bucket vertically, means for moving it laterally bodily beneath the hopper at the 105 lower end of its excursion while at the same time tilting its upper portion toward the hopper port so as to bring the two ports into register and a cut-off gate adapted to move responsive to the bucket movement and to 110 leave a free passage from the hopper to the bucket while the ports are in register, and means whereby the bucket by its motion positively moves the gate in both directions.

6. A coal handling plant comprising a 115 hopper having a discharge port, a bucket having an inlet port, means for moving the bucket vertically, means for moving it laterally bodily beneath the hopper at the lower end of its excursion while at the same time 120 tilting its upper portion about a moving pivot toward the hopper port so as to bring the two ports into register, said means comprising laterally deflected tracks with engaging devices on the bucket. 125

7. A coal handling plant comprising a hopper having a discharge port, a bucket having an inlet port, means for moving the bucket vertically, means for moving it laterally bodily beneath the hopper at the lower 130

end of its excursion while at the same time 5
tilting its upper portion about a moving
pivot toward the hopper port so as to bring
the two ports into register, said means com-
prising vertical guides and projections on
the bucket to engage therewith and laterally
diverging tracks and projections on the
bucket to engage them.

8. A coal handling plant comprising a
10 hopper having a discharge port, a bucket
having an inlet port, means for moving the
bucket vertically, means for moving its upper
portion laterally bodily beneath the
hopper at the lower end of its excursion
15 toward the hopper port so as to bring the
two ports into register, and a cut-off gate
and means whereby the bucket moves the
cut-off positively in both directions.

9. A coal handling plant comprising a
20 hopper having a discharge port, a bucket
having an inlet port, means for moving the
bucket vertically, means for moving it laterally
bodily beneath the hopper at the lower end of its excursion, while at the
25 same time tilting it toward the hopper port
about a shifting center, to bring the two
ports into register, said means comprising a

plurality of tracks and engaging members
on the bucket and adapted to engage them.

10. A coal handling plant comprising a 30
hopper having a discharge port, a bucket
having an inlet port, means for moving the
bucket vertically, means for moving it laterally
bodily beneath the hopper at the lower
35 end of its excursion, while at the same time
tilting it toward the hopper port about a
shifting center, to bring the two ports into
register, said means comprising a plurality
of tracks inclined to each other, and mem- 40
bers on the bucket adapted to engage them.

11. A coal handling plant comprising a
hopper having a discharge port, a bucket
having an inlet port, means for moving the
bucket vertically, means for tilting it 45
toward the hopper port, means for moving it
bodily laterally independent of said tilt-
ing, to bring the two ports into register.

In testimony whereof I affix my signature
in the presence of two witnesses this 12th
day of September, 1918.

HOHSON S. SHIMIZU.
